UNITED STATES PATENT OFFICE.

WILLIAM W. BEWSIC, OF RED BANK, NEW JERSEY.

MECHANISM FOR SEVERING FABRICS.

1,185,761.

Specification of Letters Patent.

Patented June 6, 1916.

Application filed September 29, 1913. Serial No. 792,380.

To all whom it may concern:

Be it known that I, WILLIAM W. BEWSIC, a citizen of the United States, residing at Red Bank, in the county of Monmouth and State of New Jersey, have invented certain new and useful Improvements in Mechanism for Severing Fabrics, of which the following is a specification.

This invention relates generally to fabric severing machines and particularly to that type of such devices utilized in severing portions of tape.

More specifically the invention relates to a machine comprising a pair of rotary members one carrying a platen or anvil and the other a severing tool or crushing member which is arranged to coöperate with the platen or anvil and crush the fibers at the point of severing, together with suitable mechanism for feeding the tape and for driving the rotary members.

The invention may be further briefly summarized as consisting in the construction and combination of parts hereinafter set forth in the following description, drawings and claims.

Referring to the drawings, Figure 1 is a side elevation of the machine; Fig. 2 is a sectional view through the center of the machine, or in other words, a section upon the line 2—2 of Fig. 3; Fig. 3 is a top plan view of the machine; and Fig. 4 is a section upon the line 4—4 of Fig. 3.

In carrying out the invention any preferred form and construction of parts may be employed so long as they possess the necessary characteristics, but I have shown one arrangement in the drawings which is effective in operation, and in such embodiment 1 represents a suitable base which is provided with a pair of side frame members 2 spaced apart properly to receive the mechanism. Each of these side frame members is provided with a vertically disposed slot 3 opening out at the top, and to the rear of this slot is another slot or recess 4 which also opens out at the top. Mounted in the slot 3 and resting on the bottom thereof is a bearing block 5 adapted to receive a trunnion 6 of an anvil or platen roll 7. Each of the blocks 5 is provided with grooves 8, shown in dotted lines in Fig. 4, so that they are guided and held within the slot 3. Each of these blocks is still further provided with an upwardly extending member 9 having a spring shank 10 for receiving the end of a

spring 11. These springs engage suitable shanks 12 carried by members 13 of bearing blocks 14 similar in all respects to the blocks 5 and supporting trunnions 15 of an upper or 60 severing roll 16. The anvil or lower roll 7 is provided with a hardened strip or anvil portion 17 extending longitudinally on the face or periphery of the anvil roll, and its exterior face forms a portion of the peripheral face of this roll. This anvil strip is adapted to coöperate with a severing strip 18 mounted in the severing roll 16 and having a severing edge 19 for engagement upon the surface of the anvil strip 17. This severing strip is hardened also.

Engaging the upper bearing blocks 14 are suitable tension screws 20 which are threaded in strips 21 secured to the upper portion of the side frame members and spanning the 75 slots 3. These screws 20 are held in any adjusted position by suitable check nuts 22. The strips 21 are held in place by suitable cap screws 23. Mounted upon the projected trunnion of the anvil roll 7 is a spur gear 24, shown in dotted lines in Fig. 2, and meshing with a gear 25 of like size keyed to the projected trunnion of the severing roll 16. The mesh of these gears is such that the severing edge of the severing strip engages 85 the anvil strip 17 during the rotation of these two parts. Mounted upon the projected trunnion 15 of the severing roll is a balance wheel 26 which is for the purpose of carrying the parts past the point when they 90 are severing the material.

Mounted in each of the slots 4 is a feed roller bearing block 27 adapted to receive the trunnions 28 of the lower feeding roll 29, shown in Fig. 2. This feeding roll has a 95 knurled exterior surface and it coöperates with a feeding roll 30 having a similar surface and provided with trunnions 31 mounted in a pair of feeding roll bearing blocks 32 also mounted in the slots 4. Springs 33 engage in sockets 34, shown in dotted lines in Fig. 4, in the blocks 32, and these springs are backed up by suitable nuts 35 mounted on screws 36 extending through strips 37 secured to the upper part of the side frame members by cap screws 38, or in any other suitable manner. Secured to the side frame members are supporting plate portions 39 and 40, the former projecting in front of the feeding rolls and having a recess for 100 permitting engagement of these rolls. This plate 39, however, stops at a point near the

engagement of the severing strip with the anvil strip. To the rear of these rolls the plate portion 40 extends to the rear for carrying out the severed articles. Mounted 5 upon the upper face of the plate portion 39 is a suitable guide 41 having an upwardly extending loop portion 42 for receiving the tape.

The lower feeding roll 29 is driven by 10 means of a gear 43 mounted upon the trunnion 28 of the lower feeding roll, and meshing with a gear 44 mounted upon the projected trunnion 15 of the severing roll.

The device is driven by a suitable driving 15 pulley 45 mounted upon the projected end of the trunnion 6.

In operation, the driving pulley 45 is driven in any suitable manner and the end 20 of the roll of tape is fed in under the guide to the feeding rolls and from thence between the anvil roll and the severing roll. As the parts rotate, the cutting edge of the severing strip engages the upper face of the fabric and crushes it on the line corresponding 25 to the cutting edge of the severing strip and the anvil. The length of strip may be either regulated by various sizes of anvil and cutting rolls, or the gear between the severing roll and the feeding rolls may be 30 varied to feed the strip either fast or slow, as the case may be, and in that way the length of the strip may be varied. The adjustment of the rolls, that is the anvil roll and the severing roll, is such that the 35 cutting edge of the severing strip just touches the face of the anvil strip so that the fibers of the tape or material operated upon are crushed on a line, and in that way severed.

40 Having described my invention, I claim:—
1. In mechanism for severing fabrics, a frame, an anvil roll supported in the frame and having a hard peripheral surface, a severing roll having a severing edge said 45 severing roll being also mounted in the frame, means for adjusting said rolls with

respect to each other so that the severing strip is coincident with the hard surface of the anvil roll but out of contact therewith whereby the fibers of the fabric are crushed to the 50 point of severing, and means for driving said rolls.

2. In mechanism for severing fabric, a frame, an anvil roll having a hardened anvil surface on the periphery, a severing roll having a severing member, supporting means arranged in the frame for both of said rolls and permitting relative movement, means for forcing said rolls apart, means for positively adjusting said rolls toward each other 60 until the edge of the severing member is coincident with the surface of the anvil portion of the anvil roll but out of contact therewith whereby all the fibers of the fabric are crushed to the point of severing, and 65 means for driving said rolls.

3. In mechanism for severing fabric, a frame, an anvil roll, a hardened anvil strip in the periphery of said roll and forming therewith an uninterrupted peripheral surface, a severing roll, a hardened severing strip arranged in said severing roll, suitable gearing between said rolls for causing the severing strip to always register with the anvil strip, supporting means for said rolls 70 arranged in the frame and permitting relative movement, springs for forcing said rolls apart, and adjusting nuts and screws for forcing said rolls toward each other against said springs until the edge of the severing 75 strip is coincident with the periphery of the anvil strip but out of contact therewith, thereby producing a severing means without the abutment of the severing strip against the anvil strip.

85 In testimony whereof I affix my signature in presence of two witnesses.

WILLIAM W. BEWSIC.
